UNITED STATES PATENT OFFICE

NETTIE FISCHMANN, OF ST. LOUIS, MISSOURI

DESIGN FOR A LADIES' SUIT

Application filed March 1, 1933. Serial No. 47,360. Term of patent 3½ years.

To all whom it may concern:

Be it known that I, NETTIE FISCHMANN, a citizen of the United States, residing in the city of St. Louis and State of Missouri, have invented a new, original, and ornamental Design for a Ladies' Suit, of which the following is a specification, reference being had to the accompanying drawing, forming part thereof.

Figure 2 is a rear view of the same.

I claim:

The ornamental design for a ladies' suit, as shown.

NETTIE FISCHMANN.
